RAILROAD SWITCH HEATER

Owen L. Garretson, Bartlesville, Okla., assignor
to Phillips Petroleum Company, a corporation
of Delaware

Application July 22, 1946, Serial No. 685,553

3 Claims. (Cl. 158—99)

1

This invention relates to gas heaters. In one of its more specific aspects it relates to gas heaters to be used in connection with railroad switches, railroad car retarders, and the like, under conditions when ice and snow are present, wherein the ice and snow are melted and such railroad mechanisms are kept in a completely operable condition.

Railroad gas burners of the prior art have had one difficulty or fault, in common, that upon passage of a high speed train, the burners could not be depended upon to remain burning. Some of the more recent and improved types of burners or heaters have remained burning during passage of a train at speeds of 60 to 70 miles per hour, but at train speeds of 100 miles or more an hour the heaters could not be depended upon.

One object of my invention is to provide an operative heating device for de-icing and preventing ice formation on certain railroad equipment, as switches.

Another object of my invention is to provide a heating device for use on railroad switches and the like, which will continue to function under conditions of passage of high speed trains.

Still another object of my invention is to provide a gas heater assembly for use in de-icing and ice prevention on railroad switch equipment and the like, which is adapted to maintain the rails and switch mechanisms at desired points in a warm or heated condition sufficient to melt ice, if present, or to prevent the formation of ice thereon and yet not maintain the rails in an overheated or inefficiently heated conditions.

Many other objects and advantages of my heater will be apparent to those skilled in the art from a careful study of my disclosure and attached drawing which respectively describes and illustrates one embodiment of my heater apparatus.

In the drawing,

Figure 1 is a side elevational view of my heater assembly.

Figure 2 is a vertical cross sectional view of my heater assembly.

Figure 3 is an end view of the cap taken from the line 3—3 of Figure 4, and shown in section in Figure 2.

Figure 4 is a sectional view of the cap taken on the line 4—4 of Figure 3.

Figure 5 is a cross sectional view of the burner orifice containing member taken on the line 5—5 of Figure 6.

Figure 6 is an end view of the burner orifice

containing member taken from the line 6—6 of Figure 5.

Figure 7 is an end view of my heater assembly. Figure 8 is a plan view of a heater installation.

Figure 9 is a side elevational view of the heater installation of Figure 8.

Referring to the drawing, and specifically to Figures 1 and 2, the heater is composed of a combustion chamber member 11, a perforate cap 12, an orifice member 13 and a gas feed assembly 14.

The combustion chamber or barrel 11 may, for convenience, be made of a section of pipe, as for example, a 1½ inch black pipe about 12 to 15 inches long. In this pipe are cut a number of slots 15, about 1/16 inch across and a half inch apart. This plurality of slots extends from the downstream end of the tube to a point near the downstream end of a combustion zone, to be described hereinafter. These slots are intended to be exits for hot combustion gases.

The burner end of this tube may carry some threads 16 for receiving the threaded end cap 12, which member may be a conventional pipe cap.

The cap 12 is drilled at its center and the opening threaded for receiving and retaining the orifice member 13. This threaded opening may be identified by reference to Figure 3, and reference number 17, thereon.

Figures 5 and 6 show detailed construction of the orifice member 13 of Figures 1 and 2. This member may be constructed of bar brass, of hexagon form, and the interior drilled out as shown. The end of the member may then be drilled with a very small drill to produce an orifice 18 for metering a combustible gas enroute to its burning zone. The size, or rather diameter, of this metering opening will be a function of the B. t. u. content of the gas to be burned in the apparatus. As is known by those skilled in the gas burner art, higher B. t. u. gases require smaller burner orifices.

The orifice end of this orifice member may be equipped with threads 19 adapted for insertion into the threaded opening 17 of the cap member 12, shown in detail in Figures 3 and 4. The opposite end may be threaded with "pipe" threads 20 adapted for attaching to a pipe coupling. The center most part of the exterior surface is permitted to retain its original hexagon form for assembling purposes.

To the pipe thread 20, end of this orifice member is attached a pipe collar or coupling 21 carrying a pipe nipple 22 at its opposite end. On the orifice end of this coupling is rigidly attached a circular plate 23. This plate contains a circular

opening at its center sufficiently large that the upstream end of the orifice member 13 may pass through freely, and yet not large enough to permit passage of the collar 21. This plate member may be welded or otherwise rigidly attached to the end of said collar as shown in Figures 1 and 2.

In the upstream end of the burner or heater tube 11 is a Venturi member 24. This member may be made from a solid metal cylinder having the Venturi opening drilled or turned out on a lathe as desired. To prevent the Venturi member 24 from sliding down the tube 11, a small shoulder or flange 25 is provided and adapted to contact the end of the tube and a set screw 26 may be inserted in a threaded opening in the tube 11 for preventing the Venturi member from moving toward the orifice member 13. Some openings 31 are provided in the bottom of the tube member 11 for disposal of water from rain or melting ice or snow in case such water finds its way into the tube.

Figures 3 and 4 shows the detail of construction of the cap member 12. As mentioned hereinbefore the center of the cap is drilled and threaded to take the orifice member 13. Upset type threads may be provided for attachment of this cap to the tube 11 so that the threads or unthreaded interior of the cap will not interfere in any manner with the flange of the Venturi member 24, and further so that the position of the cap with respect to the end of the tube 11 may be adjusted so as to promote efficient combustion beyond the Venturi throat. The end wall of the cap may carry one or more perforations or holes 27 for admission of air. Additional air inlets 28 may be provided around the circular edge of the cap. In the embodiment shown, I have provided eight quarter inch diameter holes equally spaced and the longitudinal axes of these holes 28 are approximately 45° from the longitudinal axis of the assembly. The two air inlets 27 may also be of $\frac{1}{4}$ inch diameter. It is not intended that the number or size of these air inlet openings 27 and 28 as shown is critical, since both number and size may need be varied according to the heating value of the fuel gas, and also according to the size and heating capacity of the assembly. The flange 23 is intended to prevent atmospheric wind or transversal air currents caused by a rapidly passing train from interfering with the normal inflow of air through the air inlets 27 and 28.

For installation on a railroad track, a bracket 29 as shown in Figures 1 and 2 may be welded to the top of the burner tube 11 for hooking over the bottom flange of a rail. An end bracket 30 is intended to support its end of the assembly when attached to a crosspiece member 31, the ends of which may be fastened to adjacent ties.

In assembling the burner parts, the Venturi member 24 is first inserted into the tube 11 and clamped rigidly in place by the set screw member 26. The orifice member 13 is screwed into the cap 12, and the collar 21 with its attached flange 23 is screwed to the orifice member as shown. The nipple 22 may then be placed.

The cap may then be screwed on to the threaded end of the tube 11 when the assembled heater is then ready for installation.

Figures 8 and 9 illustrate the method of installation of my heater under a pair of rails, as in the vicinity of a switch mechanism. A main line rail 33 is the fixed rail, and rail 34 is a take-off or switch rail. Of this take-off rail, rail section 38 is fixed in position, by spikes 40. Rail

section 36 is movable with a joint 35 as a pivot point.

The bracket 29 is hooked over one side of the base flange of the rail and the end bracket 30 bolted to a cross piece 31, which in turn is fastened to two adjacent ties 39 in any satisfactory manner.

After the heater is in position under the rail section to be heated, the nipple 22 may be connected to a source of gas, not shown, when the assembly is ready for service.

Placing into service involves turning on the fuel gas from a source, not shown, and application of a lighted match to the open end 32 of the tube 11, or to the slots 15, or even to the air inlet openings 27-28. Lighting the gas by way of the opening 32 or slots 15, ignites the combustible mixture issuing therefrom, the flame traveling up the tube to the downstream end of the Venturi member 24. Lighting by application of a flame to the air inlets 27-28 merely permits sucking of the flame through these air inlets and passage to the downstream side of the venturi. Even during this latter lighting operation little or no flame is present within the cap portion of the assembly since substantially no mixing of the issuing fuel gas and air occurs in this region. Mixing does occur, however, on the downstream side of the venturi and at that point it is intended for the combustion to take place. The zone from approximately the downstream end of the venturi to the first of the plurality of slots 15 is intended to be the combustion zone, and it is further intended that all or substantially all of the combustion take place within this zone. In this manner combustion gases at nearly the same temperature pass through the slots 15.

Example

For the use of propane fuel gas I have found that the Venturi throat may be $\frac{1}{2}$ inch in diameter, and two air inlets 27 of $\frac{1}{4}$ inch diameter, and eight air inlets 28 of $\frac{1}{4}$ inch diameter may be used. The size or diameter of the orifice 18 was such as resulted when a drill number 76 was used in making the orifice.

When installing a heater made according to the example, in such a manner as hereinbefore disclosed, and using propane as fuel at a pressure of 12 to 15 pounds per square inch, a railroad rail immediately over the heater was too hot to handle with bare hands, and accordingly ample heat was available to melt ice or prevent ice formation. It has been found that heat travels through the rail in both directions from the heater for a sufficient distance to protect a substantial length of rail from ice and snow.

Prior art heaters have for the most part been designed to operate on gas from municipal or utility distribution systems, and such systems ordinarily furnish gas at only a few ounces pressure, and I believe the use of such low pressure gas even in burners of best available design is one reason for failure on railroads operating high speed trains. I have found that by using gas at pressures of 10 to 15 pounds per square inch and preferably 12 to 15 pounds, burners of design as herein disclosed remain lit even during passage of trains at speeds of 100 miles per hour.

When using such as gas as an 800 B. t. u. per cubic foot city gas, the orifice 18 may be made with a No. 71 drill, and fewer holes 27-28 used.

While I have disclosed making such a heater with a $1\frac{1}{2}$ inch black iron pipe, other materials may be used. The Venturi member may be a

cast iron member, or it may be made of other material as steel or the like, providing it is adapted to casting or machining to make the Venturi opening, and is adapted to be noncorrosive and capable of withstanding heater temperatures.

The orifice containing member may well be made of brass since an orifice once made should not be subject to corrosion nor to any conditions which might alter its size or shape.

The remaining member parts may be made of standard pipe and fittings such as the nipple 22 and the collar 21. Flange 23 may be made of sheet iron or other material as desired.

If such a heater as herein disclosed is intended to be used in such service as would require a larger heater, the barrel portion may be made from a large pipe, larger in both diameter and length, and all other member parts adjusted in size accordingly. In addition the orifice then may be sized differently as well as the air inlet holes.

The heater may be supported by legs in place of the brackets 29 and 30, but I prefer to use the brackets as hereinbefore described.

As will be realized by those skilled in the art, many variations and modifications of my heater may be made and yet remain within the intended spirit and scope of my invention.

Having disclosed my invention, I claim:

1. A high pressure heater comprising an elongated hollow heater body, having end closures and being perforate in one of its sides from one end to a point near the other end so as to provide outlet for combustion gas; a high pressure fuel inlet conduit extending through a first end closure to a point adjacent the inner side of said first closure; air inlet means formed in said first closure and disposed around said fuel gas inlet conduit and to the rear of the outlet end of said fuel conduit; a venturi within and constricting said heater body at a point closely adjacent said

first closure but longitudinally spaced upstream from said perforate body portion; and deflector means on said fuel gas inlet, spaced rearwardly from said first closure so as to reduce extraneous currents about said air inlet means.

- 5 2. A high pressure heater comprising an elongated hollow heater body at least partially closed in both of its ends; a first cap member at least partially closing one end of said body, said heater body being perforate in one of its sides from a point closely adjacent the end opposite said first cap member to a point longitudinally spaced from the end closed by said first cap; a high pressure fuel gas inlet extending a short distance through said first cap member; air inlet means formed in said first cap member and disposed around said fuel gas inlet conduit and to the rear of the outlet end of said fuel gas conduit; a venturi within and constricting said heater body at a point closely adjacent said first closure but longitudinally spaced upstream from said perforate body portion; and deflector means on said fuel gas inlet, spaced rearwardly from said cap so as to reduce extraneous currents about said air inlet means; and fastener means for maintaining said heater in operational contact with members to be heated.
- 10 3. The high pressure heater of claim 2, wherein said air inlet means consists of inlets formed in the end wall of said closure cap.
- 15 20 25 30
